UNITED STATES PATENT OFFICE.

OSCAR MARTIN POLIN, OF SAN LUIS OBISPO, CALIFORNIA.

APPARATUS FOR MAKING BACKING FOR TEETH.

1,019,519.

Specification of Letters Patent. Patented Mar. 5, 1912.

Application filed July 11, 1911. Serial No. 637,982.

To all whom it may concern:

Be it known that I, OSCAR MARTIN POLIN, a citizen of the United States, residing at San Luis Obispo, in the county of San Luis Obispo and State of California, have invented new and useful Improvements in Apparatus for Making Backings for Teeth, of which the following is a specification.

The present invention relates to an improved instrument for making backings for interchangeable facings, and the object of the invention is to provide an instrument by which such backings can be made quickly and conveniently.

In the accompanying drawing, Figure 1 is a perspective view of the blank used for forming the backing; Fig. 2 is a perspective view of the same slotted; Fig. 3 is a front view of the blank for the anchor; Fig. 4 is a perspective view of the same complete; Fig. 5 is a side view of the backing with the anchor therein; Fig. 6 is a top view of the same; Fig. 7 is a rear view of the tooth showing a groove therein; Fig. 8 is a perspective view of the tooth with the backing thereon; Fig. 9 is a side view of my improved instrument for effecting the operations above indicated; Fig. 10 is a sectional view through the jaw thereof on the line 10—10 of Fig. 9.

Referring to the drawing, 3 indicates my improved instrument having jaws 5 and handles 12 for pressing said jaws together. Said jaws are formed with flat surfaces 4, 35 which contact with each other when the jaws are pressed together, and on one of said jaws at a side thereof there is secured a punch 6, a suitable die 7 being formed in the other jaw in a position to coöperate with said punch.

In using this instrument I first take a small piece 1 of plate gold of suitable form and size, (see Fig. 3) and, by means of the

instrument 3, I form said sheet gold into a hollow rib or anchor 2, (Fig. 4). This I 45 do by bending the plate gold and pressing it between flat surfaces 4 of the jaws 5 of said instrument, gradually pressing said surfaces together, and adjusting the position of the piece 1, until they are pressed together 50 so as to leave said rib or anchor of the exact form desired. By means of a punch 6 secured to one of said jaws 5, and a suitable die 7 formed in the other jaw, I punch in a blank 9 of plate gold an elongated hole 8 55 in the proper position, as shown in Fig. 2. I then insert the anchor 2 in a groove 10 formed in the tooth 11 (Fig. 7); so that the edges of said anchor extend upwardly out of said groove. The anchor being in this 60 position I then press the piece 9 of plate gold on to the inner face of the tooth, passing the slot 8 over the upturning edges of the anchor, and pressing or burnishing the plate gold on to the tooth. I then solder on 65 to said plate gold the edges of the anchor which extend slightly through said slot and the operation is complete.

I claim:

An instrument for forming backings for 70 interchangeable teeth, having jaws, and means for pressing said jaws together, said jaws having in one portion of each respectively a punch and a die for forming a slot 75 in plate metal, and in another portion thereof, two opposing flat surfaces adapted to press tightly together folded over portions of plate metal to form an anchor.

In testimony whereof I have hereunto set 80 my hand in the presence of two subscribing witnesses.

OSCAR MARTIN POLIN.
